UNITED STATES PATENT OFFICE.

JAMES C. DAWLEY, CHARLES D. DERBY, AND ALBERT G. KILIAN, OF DAYTON, OHIO,
ASSIGNORS TO THE JOYCE-CRIDLAND COMPANY, OF DAYTON, OHIO, A CORPORA-
TION OF OHIO.

LIFTING JACK.

Application filed June 19, 1924. Serial No. 721,117.

This invention relates to lifting jacks and more particularly to a lifting jack having manually actuated means for controlling the lowering of the load.

5 One object of the invention is to provide an improved mechanism whereby the actuating device for imparting lifting movement to the lifting element may be utilized to operate the mechanism which controls the downward movement of the lifting element.

10 A further object of the invention is to provide a mechanism of this character in which the controlling means will normally be positively locked against movement; and further 15 to provide means for simultaneously releasing the controlling mechanism and operatively connecting the same with the actuating device.

15 A further object of the invention is to provide a mechanism of this kind which will be simple in its construction, of a strong durable character and positive in its operation.

Other objects of the invention will appear as the mechanism is described in detail.

20 In the accompanying drawings Fig. 1 is a side elevation, partly broken away, of a jack embodying our invention; Fig. 2 is a front elevation of the same, partly broken away and partly in section; Fig. 3 is a side elevation of the actuating and controlling mechanism; Fig. 4 is a longitudinal sectional view taken centrally through the controlling mechanism; Fig. 5 is a section taken on the line 5—5 of Fig. 2; and Fig. 6 is a sectional view taken centrally through the clutch and lock mechanism.

25 In these drawings we have illustrated one embodiment of our invention and have shown the same as applied to a lifting jack of the type shown and described in Patent No. 1,443,593, granted January 30, 1923 to Ripsch, Dawley and Derby, but it will be understood that the invention may be applied to jacks of various kinds and that the mechanism may take various forms without departing from the spirit of the invention.

30 The jack as here shown, comprises a base 1 having rigidly mounted thereon and extending upwardly therefrom a tubular housing or standard 2 which, in the present instance, is screw threaded onto the base. Rigidly mounted within this standard is a screw 3 which in the present device is rigidly

secured at its lower end to a beveled gear 4 which rests upon and is supported by a bearing plate 5 which in turn is rotatably mounted on a second bearing plate 6, carried by the base 1, through the medium of a series of anti-friction balls 7. Mounted upon the screw 3 is a lifting element which is actuated by said screw to lift the load. As here shown, this lifting element comprises a nut 8 having threaded connection with the screw and having rigidly secured thereto a tubular member 9 which is slidably mounted in the standard 2 and extends above the upper end of the same where it is provided with a cap or load engaging element 10. The lifting mechanism is preferably of the high speed type and, in the present instance, the pitch of the threads on the screw and nut is such that when unrestrained the lifting element will move downward under the weight of the load.

35 Suitable operating mechanism is provided for rotating the screw and thus elevating the lifting element. In the present instance this operating mechanism comprises a rotatable member, such as a shaft 11, having at its inner end a beveled gear 12 which meshes with the beveled gear 4. This shaft is journaled in bearings 13 and 14 in a housing 15 which is rigidly secured to one side of the standard 2. The end of the shaft extends beyond the outside of the housing and has connected therewith a suitable actuating device, which is here shown as a lever socket 16, rigidly secured to a sleeve 17 mounted on the shaft 11 and rotatably mounted in a bearing 18 on the outer wall of the housing 15. A pawl 19, carried by the lever socket, engages a ratchet wheel 20 rigidly secured to the shaft 11 so that when the lever socket is rotated in one direction the pawl will engage the ratchet wheel and impart forward movement to the shaft, thereby causing the lifting element to be elevated. The lever socket has the usual socket portion 21 adapted to receive a lever or handle by means of which movement may be imparted to the actuating device.

40 Associated with the rotatable operating member or shaft 11 is suitable mechanism for controlling the downward movement of the lifting element and its load. This controlling device is of such a character that when the lifting element is so constructed that it

80

85

90

95

100

105

will move downwardly under the weight of the load the controlling mechanism will restrain this movement and thus prevent the downward movement of the load, but when 5 the lifting element will not move downwardly under the weight of the load, either because of its construction or for any other reason, the controlling device will positively move the same downwardly. The controlling mechanism 10 may take various forms but, in the present construction, it comprises a worm gear 22 rotatably mounted on the shaft 11 so that it remains stationary when this shaft is rotated in a forward direction. Means are 15 provided for automatically connecting the worm gear with the shaft when the shaft is rotated in a reverse direction. To this end the worm gear has rigidly secured thereto a clutch member 23 with which cooperates a second clutch member 24 slidably and non-rotatably mounted on the shaft 11. Springs 25 serve to press this second clutch member 24 into engagement with the clutch member 23 and the clutch teeth are of such a character 20 that when the shaft is rotated in a forward direction the teeth of the member 24 will ride over the teeth of the clutch member 23, thus permitting the shaft to rotate independently of the worm gear, but when the shaft is 25 rotated in a reverse direction the teeth of the clutch member 24 will operatively engage the teeth of the clutch member 23 and cause the worm gear to rotate with the shaft and consequently cause the worm gear to lock 30 the shaft against rotation when the worm gear is held against rotation. Cooperating with the worm gear is a worm 26 which, in the present instance, is mounted on a shaft 27 extending transversely to and arranged 35 above the shaft 11. Preferably the pitch of the threads on the spiral gear, that is, the worm and the worm wheel, is just above the critical point so that the worm wheel will not drive the worm but when the worm is stationary the worm wheel will be locked against 40 rotation. Rigidly connected with the worm 26 is a spiral gear 28 which, in the present device, is also mounted on the shaft 27. The gear 28 is rigidly connected with the gear or worm 26 and both members have hub portions or sleeves, 29 and 30, respectively, which are rigidly connected one to the other at their abutting ends. The spiral gear 28 meshes 45 with a second spiral gear 31 rigidly secured to a shaft 32 extending parallel with the shaft 11 and having secured thereto near its outer end a pinion 33. This pinion 33 meshes with a gear 34 which is mounted for rotation about the axis of the shaft 11 and is rotatable 50 independently of that shaft. In the present construction, the gear is provided with a hub portion 35 which is journaled on the outer surface of a boss 36 forming part of the bearing 14. In order to operate the spiral gearing 55 and cause the load to move downwardly,

either under its own weight or by the positive driving action of the gearing, we have provided means for connecting the gear 34 with the actuating device for the shaft 11 in such a manner that the movement of this actuating device in a reverse direction will operate the gear 34 and consequently the spiral gearing. In the present construction the hub portion 35 of the gear 34 is provided with clutch teeth 37 with which cooperate the teeth of a clutch member 38 slidably but non-rotatably mounted on the sleeve 17, with which the actuating device is connected. The clutch member 38 is moved into and out of operative engagement with the teeth 37 of the clutch member 35 by means of a yoke 39 which is here shown as annular in form and extends entirely about the clutch member 38, the latter being provided with a circumferential groove 40 to receive pins 41 carried by the yoke. The yoke is provided on its lower side with an arm 42 which is pivotally mounted between lugs 43 carried by the outer wall of the casting. The upper end of the yoke is connected with a suitable manually operated actuating device which, as here shown, comprises an arm 44 pivotally mounted on a pin or shaft 45 which is supported in lugs 46 carried by the outer wall of the housing. The lower end of the arm 44 is slotted to receive a pin 47 mounted in lugs 48 which extend upwardly from the yoke. Rigidly connected with the arm 44 and, if desired, formed integral therewith, is an outwardly extending arm 49, the outer end of which is slotted to receive a pin 50 carried by a rod or plunger 51 slidably mounted in the housing and extending beyond the upper wall thereof. In the present instance, the lower end of the rod is mounted in a socket 52 in which is arranged a spring 53 which tends to hold the plunger in its uppermost position and thereby retain the yoke and the clutch member 48 in their retracted positions. The upper portion of the rod extends through an opening in the top wall of the housing and is provided with an operating member, such as a knob 54, by means of which it may be depressed. It will be obvious that the depression of the plunger 51 will rock the arms 49 and 44 about the axis of the shaft 45 and thus cause the yoke 39 to move the clutch 38 into operative engagement with the clutch teeth 37, thereby rigidly connecting the gear 34 with the sleeve 17 and the actuating device for the shaft 11. Means are also provided for rigidly locking the controlling mechanism, or spiral gearing, against movement and thus locking the lifting element against downward movement. In the present device, this locking means operates on the gear 34 and is here shown as a dog or locking finger 55 which is mounted for movement about the axis of the pin 45 and is rigidly connected with the arm 49. The inner end of this locking member or dog 125 130

is arranged to enter a space between the teeth of the gear 34 and when in this position will rigidly hold the gear against rotation. A spring 56 acts on the locking member or dog 5 to move the same into engagement with the gear. Because of the connection between the locking member or dog 55 and the actuating arm 49 for the yoke 39 it will be obvious that when the plunger 51 is actuated to shift the 10 yoke the locking member will also be actuated to release the spiral gearing substantially simultaneously with the establishment of the connection between the same and the actuating device. In the event the lifting element 15 does not move downwardly under the weight of the load, for any reason whatsoever, and it is desirable to drive the same downwardly, it is necessary that the worm gear 22 shall be rigidly connected with the shaft 11 so as to 20 positively rotate that shaft. To this end we have provided a plunger 57 which is slidably mounted in the housing 15 and has its lower end arranged to enter the space between that clutch member 24 and a fixed part of the 25 housing, the end of the plunger being tapered so that it can be forced into this space, thereby forcing the clutch member 24 into operative engagement with the clutch member 23 and locking the same in that position. The 30 upper end of the plunger extends beyond the top wall of the housing where it is readily accessible for operation and a spring 58 acts on the plunger to hold the same normally in its elevated or inoperative position.

35 The operation of the mechanism will be readily understood from the foregoing description and it will be apparent that when the actuating device 16 is rotated in a forward direction it will be connected through the 40 pawl and ratchet mechanism with the shaft 11 and the latter will be rotated to impart lifting movement to the lifting element. The clutch 38 being in its retracted position and the locking dog 55 in engagement with the gear 34 the spiral gearing will be held against 45 rotation and the lifting element positively locked, thus rendering it impossible to move the load downwardly. When it is desired to lower the load the plunger 51 is actuated to 50 clutch the sleeve 17 to the gear 34 and to move the locking dog 55 into its inoperative position. While the plunger is held in this position the actuating device or lever socket 16 is rotated in a reverse direction, it being preferably provided with a knob or handle 59 for 55 this purpose. This rotation of the actuating device is transmitted through the clutch and gear 34 to the spiral gearing, thus rotating the same and thereby permitting the shaft 11 to 60 rotate due to the downward thrust of the load. Should the load fail to move downward under its own weight the plunger 57 is actuated to cause the worm gear 22 to be rigidly connected with the shaft so that the rotation of the worm

gear will also rotate the shaft in a reverse direction, thus driving the lifting element 65 downwardly.

While we have shown and described one embodiment of our invention we wish it to be understood that we do not desire to be limited 70 to the details thereof as various modifications may appear to a person skilled in the art.

Having now fully described our invention, what we claim as new and desire to secure by Letters Patent, is:

75 1. In a lifting jack, a lifting element, mechanism comprising an actuating member for operating said lifting element and elevating a load, mechanism to control the downward movement of said lifting element, and means for connecting said actuating member with said controlling mechanism to so actuate the latter that the lifting element will move downwardly, said actuating member being movable in one direction to elevate the load 80 and being movable in the other direction to lower the load.

2. In a lifting jack, a lifting element, mechanism comprising an actuating member for operating said lifting element to elevate 90 the load, mechanism to control the downward movement of said lifting element, a lock to hold said controlling mechanism normally against movement, and means to actuate said lock to release said controlling mechanism 95 and to operatively connect said actuating member with said controlling mechanism, whereby the latter may be operated by said actuating member to lower the load.

3. In a lifting jack, a lifting element, 100 mechanism comprising an actuating member for operating said lifting element to elevate the load, mechanism to control the downward movement of said lifting element, a lock to hold said controlling mechanism normally 105 against movement, and a single manually operated device to actuate said lock to release said controlling mechanism and to operatively connect said actuating member with said controlling mechanism, whereby the latter 110 may be operated by said actuating member to lower the load.

4. In a lifting jack, a lifting element, mechanism comprising an actuating member for operating said lifting element to elevate 115 the load, mechanism to control the downward movement of said lifting element, and means comprising a clutch for operatively connecting said actuating member with said controlling mechanism, and a device to operate said clutch.

5. In a lifting jack, a lifting element, mechanism comprising an actuating member for operating said lifting element to elevate 120 the load, mechanism to control the downward movement of said lifting element, means comprising a clutch for operatively connecting said actuating member with said controlling 125 mechanism.

mechanism, a device to operate said clutch, a lock to hold said controlling mechanism normally against movement, and an operative connection between said lock and said 5 clutch operating device.

6. In a lifting jack, a lifting element, operating mechanism for said lifting element comprising an actuating member, mechanism to control the downward movement of said 10 lifting element, means comprising a clutch for operatively connecting said actuating member with said controlling mechanism, a clutch operating member, a pivoted arm operatively connected with said clutch operating 15 member, a locking member operatively connected with said arm and movable into and out of a position to lock said controlling mechanism against movement, and a manually operated device connected with said arm 20 for actuating said clutch and said lock.

7. In a lifting jack, a lifting element, a rotatable member operatively connected with said lifting element, an actuating device rotatable relatively to said rotatable member, 25 means for operatively connecting said actuating device with said rotatable member when said actuating device is rotated in one direction, a spiral gear, means for connecting said spiral gear with said rotatable member 30 when the latter is rotated in a reverse direction, a second spiral gear cooperating with the first mentioned gear, and means operated by the rotation of said actuating device in the other direction for operating said spiral gear- 35 ing.

8. In a lifting jack, a lifting element, a rotatable member operatively connected with said lifting element, an actuating device rotatable relatively to said rotatable member, 40 means for operatively connecting said actuating device with said rotatable member when said actuating device is rotated in one direction, a spiral gear, means for connecting said spiral gear with said rotatable member 45 when the latter is rotated in a reverse direction, a second spiral gear cooperating with the first mentioned gear, and means comprising a clutch for operatively connecting said spiral gearing with said actuating device to 50 cause said gearing to be actuated by the rotation of said actuating device in the other direction.

9. In a lifting jack, a lifting element, a shaft operatively connected with said lifting 55 element, a sleeve rotatably mounted on said shaft, an actuating device carried by said sleeve, means for operatively connecting said actuating device with said shaft, a spiral gear rotatable about the axis of said shaft, 60 means for connecting said spiral gear with said shaft when the latter is rotated in a reverse direction, a second spiral gear cooperating with the first mentioned gear, a clutch member connected with said second

spiral gear, a cooperating clutch member carried by said sleeve, and means for actuating one of said clutch members to connect said actuating device with said spiral gearing. 65

10. In a lifting jack, a lifting element, a shaft operatively connected with said lifting element, a sleeve rotatably mounted on said shaft, an actuating device carried by said sleeve, means for operatively connecting said actuating device with said shaft, a spiral gear rotatable about the axis of said shaft, 70 means for connecting said spiral gear with said shaft when the latter is rotated in a reverse direction, a second spiral gear cooperating with the first mentioned gear, a clutch member connected with said second spiral gear, a cooperating clutch member carried by said sleeve, a yoke pivotally mounted at one side of said shaft and operatively connected with the last mentioned clutch member, a pivoted arm having operative connection with said yoke on the other side of said shaft, an actuating arm connected with the first mentioned arm, and an actuating rod operatively connected with said actuating 75 arm. 80

11. In a lifting jack, a lifting element, a shaft operatively connected with said lifting element, a sleeve rotatably mounted on said shaft, an actuating device carried by said sleeve, means for operatively connecting said actuating device with said shaft, a spiral gear rotatable about the axis of said shaft, 90 means for connecting said spiral gear with said shaft when the latter is rotated in a reverse direction, a second spiral gear cooperating with the first mentioned gear, a gear rotatable about the axis of said shaft and operatively connected with said second spiral gear, a clutch member carried by said last mentioned gear, a second clutch member 95 slidably and non-rotatably mounted on said sleeve, a device for shifting said second clutch member into and out of operative engagement with the first mentioned clutch member, and means for actuating said clutch shifting 100 device. 105

12. In a lifting jack, a lifting element, a shaft operatively connected with said lifting element, a sleeve rotatably mounted on said shaft, an actuating device carried by said sleeve, means for operatively connecting said actuating device with said shaft, a spiral gear rotatable about the axis of said shaft, means for connecting said spiral gear with said shaft when the latter is rotated in a reverse 110 direction, a second spiral gear cooperating with the first mentioned gear, a gear rotatable about the axis of said shaft and operatively connected with said second spiral gear, a clutch member carried by said last mentioned gear, a second clutch member slidably and non-rotatably mounted on said sleeve, a device for shifting said second clutch mem- 115 120 125

- ber into and out of operative engagement with the first mentioned clutch member, a locking member movable into and out of engagement with said last mentioned gear, and 5 means for moving said locking member into an inoperative position and for actuating said clutch shifting device to connect said last mentioned gear with the actuating device for said shaft.
- 10 13. In a lifting jack, a lifting element, a shaft operatively connected with said lifting element, a sleeve rotatably mounted on said shaft, an actuating device carried by said sleeve, a pawl and ratchet connection between said actuating device and said shaft, a spiral gear rotatably about the axis of 60 said shaft, means for connecting said spiral gear with said shaft when the latter is rotated in a reverse direction, a second spiral gear cooperating with the first mentioned spiral gear, a gear connected with said second spiral gear and rotatable about the axis of said shaft, a clutch member connected with the last mentioned gear, a second clutch member 65 operating with the first mentioned spiral gear, a gear connected with said second spiral gear and rotatable about the axis of said shaft, a clutch member connected with the last mentioned gear, a second clutch member 70 25 slidably and non-rotatably mounted on said sleeve, and a clutch shifting device for moving said second clutch member into and out of engagement with the first mentioned clutch member, whereby said spiral gearing 75 30 may be operated by moving the actuating device for said shaft in a reverse direction.
14. In a lifting jack, a lifting element, a shaft operatively connected with said lifting element, a sleeve rotatably mounted on said shaft, an actuating device carried by said sleeve, a pawl and ratchet connection 80 35 between said actuating device and said shaft, a spiral gear rotatable about the axis of said shaft, means for connecting said spiral gear 85 40 with said shaft when the latter is rotated in a reverse direction, a second spiral gear cooperating with the first mentioned spiral gear, a gear connected with said second spiral gear and rotatable about the axis of said shaft, a clutch member connected with the last mentioned gear, a second clutch member 90 45 slidably and non-rotatably mounted on said sleeve, a clutch shifting device operatively connected with said second clutch member, 95 50 a locking device movable into and out of locking engagement with said last mentioned gear, and an actuating member operatively connected with said clutch shifting device and said locking member, whereby said gear 100 55 may be released for operation and operative- ly connected with the actuating device for said shaft.
15. In a lifting jack, a lifting element, a shaft operatively connected with said lifting element, a sleeve rotatably mounted on 60 said shaft, an actuating device carried by said sleeve, a pawl and ratchet connection between said actuating device and said shaft, a spiral gear rotatably about the axis of 65 said shaft, means for connecting said spiral gear with said shaft when the latter is rotated in a reverse direction, a second spiral gear cooperating with the first mentioned spiral gear, a gear connected with said second spiral gear and rotatable about the axis of 70 said shaft, a clutch member connected with the last mentioned gear, a second clutch member 75 slidably and non-rotatably mounted on said sleeve, a clutch shifting device pivotally mounted on one side of said shaft and operatively connected with said second clutch member, an arm pivotally mounted on the other side of said shaft and operatively connected with said clutch shifting device, an actuating arm rigidly connected with said pivoted arm, a locking arm rigidly connected with said actuating arm and movable into and out of locking engagement with said last mentioned gear, and a plunger operatively connected with said actuating arm. 85
16. In a lifting jack, a lifting element, a shaft operatively connected with said lifting element, an actuating device, means for operatively connecting said actuating device with said shaft when the actuating device is rotated in one direction, a spiral gear rotatably mounted on said shaft, a one way clutch to connect said spiral gear with said shaft when the shaft rotates in a reverse direction, a second spiral gear cooperating with the 90 95 first mentioned spiral gear, a gear rotatable about the axis of said shaft and operatively connected with said second spiral gear, means for operatively connecting said last mentioned gear with said actuating device 100 for rotation thereby when the actuating device is moved in a reverse direction, and means for causing said spiral gear to be positively connected with said shaft. 105

In testimony whereof, we affix our signatures hereto.

JAMES C. DAWLEY.
ALBERT G. KILIAN.
CHARLES D. DERBY.
